CERTIFICATE OF CORRECTION

PATENT NO. : D1,099,179 S
APPLICATION NO. : 29/940613
DATED : October 21, 2025
INVENTOR(S) : Alain Blind et al.

Page 1 of 1

It is certified that error appears in the above-identified patent and that said Letters Patent is hereby corrected as shown below:

On the Title Page

Item (72) Inventors:

“Karim Jedlitschka, Halle (DE)”

Should be replaced with:

“Karim Jedlitschka, Halle (Westfalen) DE”

Item (72) Inventors:

“Maximilian Gr+e,uml o+ee tsch”

Should be replaced with:

“Maximilian Grötsch”

Item (72) Inventors:

“Maren Luetkebomk, uml u+ee tersloh (DE)”

Should be replaced with:

“Maren Luetkebomk, Gütersloh (DE)”

Item (30) should be add and should read:

“EM 015038739-0001 filed on December 15, 2023”

Signed and Sealed this
Sixteenth Day of December, 2025

John A. Squires
Director of the United States Patent and Trademark Office
